UNITED STATES PATENT OFFICE.

CHESTER H. BEACH, OF RACINE, WISCONSIN, ASSIGNOR TO WISCONSIN ELECTRIC COMPANY, A CORPORATION OF WISCONSIN.

DRINK MIXER.

Application filed May 14, 1923. Serial No. 638,739.

My invention relates to improvements in drink mixers such as are used on soda fountains.

The object of my invention is to provide a simple portable device of this character. A contributory object is to provide a supporting standard from which the motor may be readily lifted by hand to permit a receptacle to be placed beneath it so that the stirring device or agitator may be lowered into the receptacle or lifted from it without providing an elaborate mechanism permitting a counterweighted motor to be slid up and down on a supporting structure, as has been done heretofore. An additional object is to provide a smooth running, finely balanced agitator rod. This is accomplished largely by forming said rod as an extension of the armature shaft instead of a separate part to be attached thereto.

In the drawings I have illustrated one embodiment of my invention.

Figure 1 is an elevation thereof partly in section; and Fig. 2 is an elevation at right angles to that in Fig. 1.

The equipment includes a supporting base 1, preferably in the form of a casting having an upright standard thereon which may be formed of a metal rod 2, having its middle portion bent to form a ring 3, the ends of said rod being seated within openings in the base and suitably secured therein. The portion of the rod which is formed into a supporting ring structure is surrounded by a cushioning material, preferably a rubber tube 4, slipped over the rod as shown.

The motor 5 may be of any suitable type and has a shoulder 6 thereon formed where the lower section of the motor casing fits into the upper section. Said shoulder enables the motor to be supported by said ring when lowered by hand into the position shown in the drawings. The armature shaft 7 is extended to form a spindle 7 having an agitator 8 secured to the lower end thereof. The device is lifted by an insulating handle 9, which is preferably of cylindrical form, and is spaced above the upper end of the motor by hollow insulating tubes 10. The hollow handle contains a suitable switch 11, preferably of the type having two stems 12, projecting from opposite sides whereby either stem may be readily pushed inward

by hand. The handle is held to the motor by 55 screws 13 passing through the hollow tubes 10, one of said tubes serving also to enclose conductors 14, which lead from the motor to the switch and to the external circuit conductors 15.

The receptacle 16 rests on a yielding pad 17 made preferably of rubber, the operator being aided in positioning said receptacle centrally, by a pair of pins 18, projecting from the said base, which latter is provided 60 with a rubber ring 19 on the lower side thereof to prevent marring the surface of the support on which said base rests.

The agitator rod 7, constituting an integral part of the armature shaft, is supported at its upper end in a spherical babbitt bearing 20, which latter is seated in a spherical pressed steel shell 21. A sheet metal cap 22 completes the enclosure and is secured to the motor casing to prevent turning. The 75 agitator shaft has a shoulder 23 resting on the cap 22. The arrangement is such that a ball and socket joint is provided permitting a slight deviation of the agitator shaft from the center axis of the upper part of 80 the motor casing, in case any slight inaccuracy develops in assembling the interfitting upper and lower parts of said casing, which join at the shoulder 6. An oil wick 24 is provided to oil the bearings and an oil guard 85 25 surrounds the agitator rod near the upper end thereof to prevent an occasional drop of oil from dripping into the beverage which is being mixed, and also to prevent such oil from being scattered by centrifugal force. 90 The diameter of the said agitator rod below said cap is slightly less than above the same which facilitates assembling of parts, the reduced diameter resulting in a slight shoulder 26. 95

Motors of this character operate at very high speeds, for example 12,000 revolutions per minute. The armature, therefore, should be very carefully balanced to avoid excessive vibration. The agitator rods employed heretofore, have been formed as separate parts attached to the armature shaft. Under such circumstances, it is almost impossible to center the agitator rod with the same degree of accuracy as the nicely balanced armature shaft, and therefore the rapid rotation of the agitator shaft results in vibration of the motor, off-setting the

care and efforts expended in balancing the latter. This difficulty has been overcome, however, in the construction disclosed herein, and the expense of manufacture has also 5 been reduced.

The agitator 8 is also very carefully made, and to avoid vibration of the agitator rod, is carefully centered therein by means of a stud 27 having a short cylindrical surface 10 which centers said stud independently of the screw threads. As a result, all the rotating parts run very smoothly even at exceedingly high speeds.

In using the device, the operator simply 15 lifts the motor from the supporting ring by means of the handle and places the receptacle beneath said ring, thereafter lowering the motor and operating the switch with the same hand thus starting the motor and 20 stirring the contents of said receptacle. After the mixing operation has been completed, the operator simply lifts the motor from its support at the same time throwing off the switch and with the other hand re- 25 moves the receptacle and thereafter places the motor on the ring where it remains until the next mixing operation. The ring is supported at one side only by the rods 2, so that it overhangs the base 1, making it easy 30 to position the receptacle on the base and remove it therefrom, without interfering with said rods. The construction described is very simple mechanically, inexpensive in 35 construction and convenient to manufacture and to manipulate. It is also sanitary. The handle or switch may be located on some other part of the motor, the side, for example, and various other rearrangements of parts or modifications of design will 40 readily suggest themselves.

I claim:-

1. A drink mixer comprising a support for a receptacle, an upright member secured to said support and arranged at one side of 45 said receptacle, a supporting device extending horizontally from said upright member at an elevation above the top of said receptacle, whereby said receptacle may be placed on said support and removed therefrom 50 with one hand without interference by said upright member or said supporting device, the latter device having an opening, a motor having a casing which fits said opening, whereby it may be positioned centrally 55 above said receptacle and freely lifted therefrom, and an agitator depending from said motor into said receptacle to stir the contents thereof when said motor and receptacle are in operative relation to each other.

60 2. A drink mixer comprising a support for a receptacle, an upright member secured to said support and arranged at one side of said receptacle, a supporting device extending horizontally from said upright mem- 65 ber at an elevation above the top of said re-

ceptacle, whereby said receptacle may be placed on said support and removed therefrom with one hand without interference by said upright member or said supporting device, the latter device having an opening, a 70 motor having a casing which fits said opening, whereby it may be positioned centrally above said receptacle and freely lifted therefrom, a handle on the top of said motor to facilitate such removal, and an agitator depending from said motor into said receptacle to stir the contents thereof when said motor and receptacle are in operative relation to each other.

3. A drink mixer comprising a support for 80 a receptacle, an upright member secured to said support and arranged at one side of said receptacle, a supporting device extending horizontally from said upright member at an elevation above the top of said receptacle, whereby said receptacle may be placed on said support and removed therefrom with one hand without interference by said upright member or said supporting device, the latter device having an opening, a motor 90 having a casing which fits said opening, whereby it may be positioned centrally above said receptacle and freely lifted therefrom, a handle on said motor casing having a switch associated therewith, whereby the motor circuit may be opened or closed by hand as said motor is being lifted from or returned to operative position over said receptacle, and an agitator depending from said motor into said receptacle to stir the contents thereof when said motor and receptacle are in operative relation to each other.

4. A drink mixer comprising a motor with a depending agitator, the motor casing having a shoulder thereon, a ring to receive said casing and engage said shoulder to support said motor, a substantially vertical standard to the top of which said ring is secured, said standard having a base located beneath said motor and ring to support the latter in stable equilibrium at an elevation above the top of the receptacle whose contents are to be stirred, said standard being located at one side of said receptacle, whereby the latter may be placed beneath said ring or removed therefrom by hand without obstruction, whenever said motor is lifted from said ring to prevent interference between said depending agitator and said receptacle, into which it normally projects when both are in operative position.

5. A mixing apparatus comprising a support for a receptacle, an upright member secured to said support and arranged at one side of said receptacle, a motor having a casing and an agitator depending from said motor into the receptacle to stir the contents thereof, and a supporting device secured to and extending laterally from said upright 125

member over the top of said receptacle and having a ring-like portion of greater diameter than the motor casing to embrace the motor casing at the side thereof and position 5 the motor against lateral displacement, said supporting device holding the motor in operative position with respect to the receptacle, said motor being freely liftable from said supporting device so that said agitator 10 may be raised out of said receptacle and said receptacle being freely movable laterally into and out of position on its support when the motor and its agitator are so lifted.

6. A mixing apparatus comprising a support 5 for a receptacle, an upright member secured to said support at one side of the receptacle, a motor having a casing and an agitator depending from said motor into the receptacle to stir the contents thereof, and 20 a supporting device for holding the motor vertically in operative relation to the receptacle, extending laterally from said upright member over the top of the receptacle and having a motor engaging portion constructed 25 to embrace the motor casing in a region above the lower face thereof so as to position it laterally, said motor and agitator being freely liftable from said supporting device to permit the receptacle to be moved into and 30 out of position on said receptacle support.

7. A mixing device of the class described, comprising a motor having a vertical armature shaft and a substantially cylindrical casing with a horizontal band encircling the same at the middle thereof and projecting 35 therefrom to form an annular support, an agitator shaft depending from said vertical armature shaft in alignment therewith, with its lower end free and unsupported and having an enlargement thereon, a horizontal support 40 for said motor having an opening thereon to receive part of said cylindrical casing with the lower edge of said band resting on the margin of said opening, an upright member 45 to which one side of said support is connected, a stand on which a receptacle may rest beneath said motor and having an opening at one side to receive the lower end of said upright member and thus support the motor with its agitator shaft extending substantially centrally into said receptacle to 50 stir the contents thereof, and a handle associated with said motor casing whereby said motor may be freely lifted from its support to permit said receptacle to be removed laterally from said stand.

In testimony whereof, I have subscribed my name.

CHESTER H. BEACH.
